(57) **CLAIM**

The ornamental design for LED with a lens, as shown and described.

DESCRIPTION

FIG. 1 is a perspective view of a LED with a lens showing our new design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view.

The broken line showing of the environment is for illustrative purpose only and forms no part of the claimed design.
